UNITED STATES PATENT OFFICE.

ISAAC SANTOS Y SUAREZ AND ROBERTO DE AROZARENA Y MENDIVE, OF HABANA,
CUBA.

INTERNAL-COMBUSTION MACHINE.

1,349,111.

Specification of Letters Patent. Patented Aug. 10, 1920.

Application filed October 4, 1919. Serial No. 328,490.

To all whom it may concern:

Be it known that we, ISAAC SANTOS Y SUAREZ and ROBERTO DE AROZARENA Y MENDIVE, citizens of Republic of Cuba, residing at the city of Habana, Republic of Cuba, as above stated, have invented new and useful Improvements in Internal-Combustion Machines, of which the following is a specification.

10 The object of this invention is to apply the energy used in internal combustion engines, in other words, the expansive force of compressed and burnt gases to pistons rotating within a casing or chamber and as 15 these pistons are connected to a central shaft by means of a wheel, this shaft will also rotate.

This machine, owing to the mechanism which we desire to have patented, has the 20 four strokes of the ordinary four-cycle engine, *i. e.* suction, compression, explosion and exhaustion.

With reference to the accompanying drawings, in description and explanation of 25 our improved mechanism, the object of our patent:

Figure 1 is a side view of the motor;

Fig. 2 is a vertical section thereof, taken 30 approximately on the line 2—2 of Fig. 4;
Fig. 3 is a vertical transverse section, taken approximately on the line 3—3 of Fig. 1; and,

Fig. 4 is a plan view of the motor.

The pistons *g*, *h*, *i*, rotate within a chamber *O*, and are secured to the wheel 12, (Figs. 1, 2, 3,) and this wheel is attached to the central shaft 1, (Fig. 3). When the pistons rotate, the wheel 12, and the shaft 1, also rotate and to this latter, gear 2, and 40 cams 3, and 4, are connected, (Figs. 1, 2, 3). The gear 2, when turning, moves pinions 7 and 8, (Fig. 1) by means of a chain, and these pinions give movement to the cams 9, 10, 11, and 14, which open the valves *c*, *d*, *e*, 45 and *f*, (Figs. 1, 2, 4). The springs, fastened to the stems of these valves, close them when not held open by the cams. The cams 3, and 4, open the slide-valves *a* and *b*, and the springs fastened to them close the valves 50 when not held open by the cams. The slide valves *a*, and *b*, (Fig. 5,) when not opened by the cams, close chamber *O*, completely, and, when opened, leave free way to the pistons *g*, *h*, *i*.

The operation of the motor is as follows:

When the piston *g*, rotates in the chamber *O*, in the direction *g*, *h*, *i*, shortly after it reaches the slide-valve *a*, this valve closes and valve *e*, opens. This valve is connected 60 with a carbureter by the tube *K*, and as the piston *g*, advances in the chamber *O*, and the slide-valve *a*, being closed, the piston *g*, sucks the gas from the carbureter, through the valve *e*, and the opening *m*, into the 65 chamber *O*. Shortly before the piston *g*, reaches the slide-valve *b*, this valve opens and remains open until the piston has passed when it closes again. The valve *e*, also closes and the gas is in the chamber *O*, between the slide-valves *a*, and *b*, then the piston *i*, is near the slide-valve *a*, which opens and the piston begins to compress the gas which is in the chamber *O*, against the slide-valve *b*. The valve *d*, then opens and the 75 compressed gas passes through the opening *r*, and the valve *d*, to the tube *J*. In the meantime, piston *i* advances and as soon as it passes the opening *p*, through which the valve *c*, is in communication with the chamber *O*, the valve *c*, opens and the compressed gas which is in the tube *J*, passes to the chamber *O*, between the slide-valve *a*, which is closed, and the back part of piston *i*. As soon as the compressed gas has passed the 80 valve *c*, closes and there is an electric spark from the spark-plug that is placed in the opening *q*, which causes combustion of the compressed gas in the chamber *O*, between the slide-valve *a*, and the back part of the 85 piston *i*, and the expansion resulting therefrom forces the piston *i*, toward the slide-valve *b*, which opens before the piston reaches it and closes immediately after it has entirely passed. Then the piston *h*, 90 which also rotates, is before the slide-valve *a*, which opens, and the piston *h*, finds chamber *O*, full of burnt gases. The slide-valve *b*, is closed and the valve *f*, then opens, which valve is connected to the chamber *O*, 95 through the opening *s*, and the piston *h*, expels the burnt gases through the valve *f*, and the tube *l*. As soon as the piston passes the slide-valve *a*, this closes and the valve *e*, opens and the piston *h*, begins to suck 100 the gases from the carbureter through the tube *K*, and the operation continues so on 105 successively.

The pistons *g*, *h*, *i*, and the slide-valves *a*, and *b*, have expansion springs of a rectangular form.

All the movements regulating the valves, etc., are operated by well known mechanical devices and are indicated in the drawings by numbers.

Claims:

1. An internal combustion engine, comprising a casing provided with an annular chamber, a shaft mounted for rotation in said casing, a plurality of members secured to said shaft and adapted to traverse said annular chamber, a pair of members adapted 15 to slide radially of said annular chamber, thereby to form an explosion chamber within said annular chamber, said explosion chamber being provided with a plurality of valve-controlled inlet and outlet passages, 20 communicating means between one of said inlet passages and one of said outlet passages, and means for operating the slidable members and valves in proper sequence for admitting an explosive charge to said explosion chamber during the passage there- 25 through of one of said traversing members, and for establishing communication between the said communicating inlet and outlet passages during the passage of another

of said traversing members through the explosion chamber.

2. An internal combustion engine as set forth in claim 1, the valve-operating means comprising a plurality of cams mounted for rotation on said casing, and a wheel secured 35 to said shaft and adapted to cause rotation of said cams.

3. An internal combustion engine as set forth in claim 1, the means for operating the slidable members comprising a pivoted 40 lever secured to each of said slidable members, and cams secured to said shaft and adapted to swing said levers on their pivots.

4. An internal combustion engine as set forth in claim 1, the valve-operating means 45 comprising a plurality of cams mounted for rotation on said casing and a wheel secured to said shaft and adapted to cause rotation of said cams, and the means for operating the slidable members comprising a pivoted 50 lever secured to each of said slidable members and cams secured to said shaft and adapted to swing said levers on their pivot.

In testimony whereof we have signed our names to this specification.

ISAAC SANTOS Y SUAREZ.
ROBERTO DE AROZARENA Y MENDIVE.
